UNITED STATES PATENT OFFICE.

R. A. SIMMONS, OF VERNONIA, OREGON.

REVERSIBLE-FLOW DRY KILN.

Application filed July 13, 1925. Serial No. 43,274.

The object of my invention is to provide air circulating and conditioning—the latter referring to temperature and moisture—means economically operated.

To recirculate air which has become excessively laden with moisture absorbed from the lumber pile is wasteful.

To induce a natural draft through the medium of air inlets and a stack is most economical but too slow; merely heating the circulated air is not found efficient. Hence, a forced draft was resorted to, the forced draft commonly being attained by forcing in exterior air and in that way displacing the saturated air. But the means necessarily employed for such purpose greatly increase the cost of operation.

It has long been desired to provide efficient air circulation in the kiln by means relatively simple and inexpensive to operate. I have discovered that this result may be attained by inducing a low pressure vacuum within the kiln through the medium of a stack, and associating with the air-inlet of the kiln means functioning both to condition the air—as to temperature and moisture—and inducing its movement. I attained this result by associating with the air inlets heating coils and steam sprays which in cooperation with the low vacuum induced by the stacks cause the efficient circulation of the air in the kiln. And by providing two groups of said agencies—one at the middle of the kiln, under the pile of lumber, and the others at the sides, and in conjunction therewith means for controlling each group of inlets, and air conditioning and moving means as a unit—the direction of air circulation within the kiln may be controlled.

The details of construction and mode of operation of my invention are hereinafter described with reference to the accompanying drawings, in which:

Fig. 1 is a foreshortened plan section through a dry kiln embodying my invention with some portions being shown as broken away to disclose details of construction;

Fig. 2 is a diagrammatic vertical section through my improved dry kiln showing the arrangement of the devices relatively to each other and the path of the circulated fluids through the kiln in one direction; and

Fig. 3 is a similar section with the devices arranged to reverse the path of the circulation, the arrows in said figures indicating the reversed flow through the kiln.

My improved kiln *a* is provided with doors *a'* at one end through which the car *b* carrying the loosely stacked lumber *c* may be admitted, said car preferably running on tracks *d* extending longitudinally of the kiln. Said tracks are supported by spaced stringers *e* which thus constitute a skeleton floor and beneath said stringers the air inlet pipes *f*, *f'* and *g* are mounted. Perforated steam pipes *h*, *h'* and *i* are preferably carried directly on said air inlet conduits *f*, *f'* and *g*, respectively. The perforations are arranged as diagrammatically illustrated in Figs. 2 and 3 so as to emit jets of steam vertically. The slotted perforations *f²*, *f³* and *g'* in the air conduits *f*, *f'* and *g*, respectively, are also arranged at the top of the respective conduits, as shown in Fig. 1, so as to direct jets of air upwardly, vertically. Arranged in vertical alinement with said conduits *f*, *f'* and *g* are heating coils *j*, *j'* and *k*, respectively, which are heated by steam being passed therethrough. Said pipes are imperforate and are merely used to heat the air emitted from the conduits, *f*, *f'* and *g* by the heat which is radiated through their walls. Baffles *l* are arranged to separate the side air conduits *f*, and *f'* and the corresponding heating coils *j* and *j'*, from the central air conduit *g* and the central heating coils *k*. Said baffles extend downwardly to a point below the slotted perforations in said air conduits, and flare outwardly at their tops, as shown in Figs. 2 and 3, so as to direct the flow of air from the middle conduit *g* across the entire stack of lumber *c*. They correspondingly direct the flow of air when reversed so that it will be directed between said baffles when descending through said stack of lumber so as not to interfere with the ascending streams of heated air and steam passing around the sides of said stack. I arrange the vents *m* in the walls of the kiln with their mouths opening directly below the air conduits *f* and *f'*, as shown in Fig. 2.

Thus I am able to reverse the circulation of air in the kiln, by shutting off the center set of heat and moisture supplying elements, and turning on the side heat and moisture supplying elements.

When the center elements are functioning, the hot moist air will rise through the pile of material to the top of the kiln and descend at the sides passing out through the air outlets located on the floor of the kiln,

and when the side heat and moisture supplying elements are actuated and the center elements are turned off, the air will rise to the side of the pile and descend through the pile to the floor of the kiln and pass along the floor and out through the air outlets, being drawn therethrough by the draft created through the stack into which the air outlets lead.

10 The moist air is warmer than the atmosphere and in passing upward through the vents tends to produce a "stack effect," that is, to create a draft through the conduit and thus to draw additional fresh air as before mentioned into the kiln through the vents f , f' and g .

15 If desirable said conduits may extend entirely through the walls of the dry kiln and open at each end; thus the air can be drawn in through both ends of the kiln. In the latter event, control devices similar to the valves r' , r^2 and r^3 , which are hereinafter described, must be provided for controlling the flow of air through both ends of said

20 conduits.

25 Steam is provided from some suitable generator and supplied through the main supply pipe o which branches and supplies steam for the heating coils j , j' and k through the branch pipes o , o' and o^2 . The branch pipe o^2 has a further branch o^3 therefrom which supplies steam to the perforated humidifying pipes i . Other branch steam pipes o^5 and o^6 , provided with a common connection, supply steam to the perforated humidifying pipes h and h' , respectively. Each of said pipes are provided with valves p' for the heating coil j , p^2 for the humidifying pipes h and h' , p^3 for the heating coils k and for the humidifying pipes i , and valve p^4 for the heating coils j' . Valves are provided for the air conduits f , f' and g also, said valves being respectively marked r' , r^2 and r^3 . All of said valves are preferably connected by a single pull rod s so that by pushing the rod in one direction all of the valves will be arranged to cause the circulation of fluid in one direction in the kiln and by pulling the rod in the opposite direction said circulation will be reversed. This is because the valves r' and r^2 in the air conduits h and h' will open with the rod in the position shown in Fig. 1, and the valve r^3 in the conduit g will be closed. Correspondingly the valves in the heating coils j and j' and h and h' are open while the valves in the heating coils k and the humidifying pipes i are closed. This condition will

be reversed by moving the pull rod in the opposite direction. As shown in the figures, 60 the conduit g is twice the size of the conduits f or f' , or in other words, its capacity is equal to the summation of the capacity of both. Each of the heating coils j and j' are one-half the size of the heating coils k and 65 the perforated humidifying pipes h and h' are single while the pipes i are double and of the same size. By arranging the devices in this manner an equally effective circulation is arranged by causing the side elements 70 to be actuated to produce circulation in one direction or to cause the middle elements to be actuated to produce circulation in the opposite direction.

I claim:

75 1. In a dry kiln, in combination with means for supporting a pile of material spaced from the floor of the kiln, air-inlets, one located at the middle and one at each side of the kiln adjacent its floor, air-outlets 80 located at each side of the kiln under the air-inlets, said air-outlets opening into stacks respectively, partitions separating the air-inlet at the middle from those at the sides of the kiln, such partitions extending downward in close proximity to the floor, spray pipes and heating coils associated with each air-inlet whereby exterior air is drawn into, 85 conditioned and induced to circulate through the kiln, and is removed again by the stacks, 90 for replacement by the admission of further exterior air.

95 2. In a dry kiln, in combination with means for supporting a pile of material spaced from the floor of the kiln, air-inlets, one located at the middle and one at each side of the kiln adjacent its floor, air-outlets located at each side of the kiln under the air-inlets, said air-outlets opening into stacks respectively, partitions separating the air-inlet at the middle from those at the sides of the kiln, such partitions extending downward in close proximity to the floor, spray pipes and heating coils associated with each air-inlet and means for 100 controlling each group of air-inlets and the spray pipes and heating coils therewith associated as a unit, thereby to control the direction of the circulated air currents, whereby exterior air is drawn into, conditioned and induced to circulate through the kiln, and is removed again by the stacks, for replacement by the admission of further exterior air.

110 R. A. SIMMONS.
